UNITED STATES PATENT OFFICE.

LUES REITER AND HARRY FULFORD, OF PROVIDENCE, RHODE ISLAND.

SEPARABLE FASTENER.

1,109,179.

Specification of Letters Patent.

Patented Sept. 1, 1914.

Application filed July 11, 1913. Serial No. 778,482.

To all whom it may concern:

Be it known that we, LUES REITER and HARRY FULFORD, citizens of the United States; and residents of the city of Providence, in the county of Providence and State of Rhode Island, have invented certain new and useful Improvements in Separable Fasteners, of which the following is a specification.

10 This invention relates to socket members for separable fasteners, and has for its object to provide a socket member of this character formed from a single piece of sheet metal with an inner and an outer plate 15 integral at their edges, the inner plate being provided with a plurality of resilient fingers folded outward near their middle portion and the periphery of said plates being rolled over the free ends of said fingers so as to 20 yieldably retain them in position, whereby the head of a complementary stud may be readily passed into said socket and removably but firmly secured thereto.

The invention further consists in providing the outer plate with a central opening and rolling the stock around said opening inward to provide a bead over which the outer member is rolled for permanently securing the whole in position on the goods.

25 30 A further object of the invention is to swage the stock of the fingers slightly inward at a point between the base and the bend thereby stiffening the stock of the fingers and providing a contracted neck portion 35 through which the head of the stud must pass to enter the enlarged portion within adapted to receive it.

With these and other objects in view, the invention consists of certain novel features 40 of construction, as will be more fully described and particularly pointed out in the appended claims.

45 Of the accompanying drawings: Figure 1— is an enlarged sectional elevation showing the socket member permanently secured by means of the cap to the material or goods and the stud in position to enter the socket. Fig. 2— is a plan view showing the shape of the blank from which the socket member 50 is formed. Fig. 3— is a sectional elevation showing another step in the operation wherein the blank is bent to form an inner and outer plate and a plurality of fingers extending outwardly from said inner plate. 55 Fig. 4— is a sectional elevation showing the finished socket member with the ends of the

60 fingers extending under the rolled over periphery of said plates and the edge of the stock around the central aperture in the outer plate being rolled inward to form a bead. Fig. 5— is a plan view of the socket member.

65 Our improved socket member is preferably formed from a single piece of sheet metal, the same being provided with a plurality of fingers 10, the number preferably employed being four. The outer ends of these fingers are preferably formed with a V-shaped notch forming points 11—11 which are adapted to be more readily bent 70 to pass under and be engaged by the rolled over peripheral edge presently described. The body portion of this member is bent into the form illustrated in Fig. 3 comprising an outer plate 12 preferably bent into 75 a concavo-convex shape and then doubled practically upon itself forming an inner plate 13 having its outer edge integral with that of the outer plate 12. The fingers 10 are formed to extend outward from this 80 inner plate and are bent near their middle portion, as at 14, said bent over portion 15 extending on an outward angle with its pointed ends resting on the inner plate and near its periphery. That portion of the 85 fingers between the bend and the inner plate is offset inwardly as at 18 forming a contracted neck portion and a comparatively enlarged inner socket portion for receiving and retaining the head of the stud 19, see 90 Fig. 1. In order to secure the ends of these fingers in position the peripheral folded edge 16 of these plates 12 and 13 is rolled inward forming an undercut or groove 17 into which these finger ends extend. The 95 outwardly extending portion 15 of the fingers serve to stiffen and support their gripping neck portion whereby said fingers will retain the head of the stud in its socket portion against considerable strain to withdraw it. 100

105 It is found in practice that where fasteners of this character are applied to such small light articles as ladies' gloves and the like, that they should release with a comparatively slight pull, but where fasteners of this character are applied to suspenders, automobile tops, clothing, and the like, where it is necessary to resist considerable strain, it is found necessary to support and 110 stiffen the gripping fingers so that they will resist considerable strain and will not

permit the head to be too readily drawn from its socket, therefore to accomplish this our present construction provides supports for said fingers set on an angle thereto to 5 extend from the periphery of the plate to the outer or engaging ends of said fingers to support and materially stiffen the same. Another feature of this invention is that the outer plate 12 is provided with a central 10 opening 20, the stock at the edge of which is rolled inward as at 21, see Figs. 1 and 4, providing a bead which serves a double purpose, first, to stiffen the stock at this point around the opening, and second, to provide 15 a means for retaining the neck of the cap, presently described. This socket member is designed to be permanently secured to the article or goods *a* by means of a cap member 22, said cap member being provided 20 with an enlarged finished head 23 and a neck portion 24 the end of the stock at the neck portion being adapted to be passed through a hole in the goods and through the opening 20 in the outer plate 12 of the 25 socket member. The edge of this neck portion 25 is then bent and rolled over the inwardly formed bead of this outer plate thereby positively and permanently securing the socket member to the goods.

30 We claim:

1. A socket member consisting of a single sheet of material bent upon itself to form a base comprising inner and outer plates, the inner edge of said inner plate having a plurality of integral spring fingers bent downwardly with their ends resting upon the outer edge of said inner plate, the 35

periphery of said base being folded upon the ends of said fingers to clamp them in position.

2. A socket member consisting of a single sheet of material bent upon itself to form a base comprising inner and outer plates, the inner edge of said inner plate having a plurality of integral spring fingers bent downwardly with their ends resting upon the outer edge of said inner plate, said tongues being offset between the bend therein and said inner plate to form an enlarged socket, and the periphery of said base being folded 40 upon the ends of said fingers to clamp them in position.

3. In a separable fastener, a socket member consisting of a single sheet of material bent upon itself to form a base comprising inner and outer plates, said outer plate having a central opening, the inner edge of said inner plate having a plurality of spring tongues bent downwardly and outwardly with their ends resting upon the outer edge 45 of said inner plate, the periphery of said base being bent upon the ends of said fingers to clamp them in position, and means passing through the opening in said outer plate and engaging the periphery thereof for securing said socket upon a fabric.

In testimony whereof we affix our signatures in presence of two witnesses.

LUES REITER.
HARRY FULFORD.
